[57] CLAIM

The ornamental design for an instrument for drawing a music staff or the like, substantially as shown and described.

DESCRIPTION

FIG. 1 is a perspective view of an instrument for drawing a music staff or the like showing my new design; FIG. 2 is a rear elevational view; FIG. 3 is a top plan view; FIG. 4 is an end elevational view; FIG. 5 is a front elevational view with the cover removed to expose the pen elements; and FIG. 6 is a rear perspective view thereof.
